United States Patent Office.

WILSON BOHANNAN, OF BROOKLYN, NEW YORK.

Letters Patent No. 67,401, dated August 6, 1867.

IMPROVEMENT IN PADLOCKS, &c.

The Schedule referred to in these Letters Patent and making part of the same.

TO ALL WHOM IT MAY CONCERN:

Be it known that I, WILSON BOHANNAN, of Brooklyn, in the county of Kings, and State of New York, have invented an Improvement in Locks; and I do hereby declare the following to be a full, clear, and exact description thereof, reference being had to the accompanying drawings, making part of this specification, in which—

Figure 1 is a front view of a padlock having my improvements applied to it.

Figure 2 is a similar view of the same parts, showing the shackle locked in place.

Figure 3 is an enlarged section through the lock taken in the plane indicated by red lines *xx* in fig. 1.

Figure 4 is an enlarged section view, showing the construction of the parts which are applied to and move with the bolt frame.

Figures 5 and 6 show modified forms of the lock mechanism.

Figure 7 is a perspective view of the key.

Similar letters of reference indicate corresponding parts in the several figures.

This invention relates to certain novel improvements on burglar-proof locks, wherein notched sliders are employed in conjunction with a straight-edge knife or plate, so arranged that when the notches in all of the sliders are brought in a plane with the knife by the insertion of a flat key, the lock-bolt can be freely moved.

The nature of my invention consists in applying the knife or safety-guard of the lock that its straight edge will approach and recede from the notches in the sliders in a plane parallel to the edges of these sliders, so as always to enter said notches squarely, notwithstanding the fact that the sliders are moved, with their bearing-plate, in the arc of a circle, as will be hereinafter described.

To enable others skilled in the art to understand my invention, I will describe its construction and operation.

In the accompanying drawings, figs. 1, 2, 3, and 4, A represents the lock frame of a padlock, A' is the face-plate which is shown in fig. 3, and B is the shackle which is pivoted to the stud B², and constructed with a recess or slot throughout its nose B¹ for receiving the hooked bolt *a* of the oscillating frame, C. This frame A and its shackle B may be constructed in a manner similar to like parts of padlocks heretofore made. The frame C is constructed with the hooked lock *a* upon its upper extension, which enters the slot in the nose of the shackle when the latter is locked, as shown in fig. 2. This frame C is pivoted to a stud, *p*, on the inside of the back-plate of the lock frame A, so that it will oscillate freely about said pivot a sufficient distance to lock and unlock the shackle. A recessed elevation or boxed bearing, *d*, is secured to or formed upon the plate C, for the purpose of receiving and serving as a guide and holder for the notched sliders *e e*. The circular end of this boxed bearing *d* is slotted, as shown in figs. 1 and 2 and 3, for the purpose of receiving through it a thin key, K, of the kind shown in fig. 7, so that the wards S of this key will push back in several sliders the required distances to allow of their respective deep notches to be brought in the same line. This circular end of bearing *d* passes freely through the face-plate A', as shown in fig. 3, and consequently forms an outer pivotal bearing for serving, in conjunction with the inner pivotal bearing *p*, as a means of holding the plate C in place within the lock frame. The sliders are made with false and true notches in them, in the usual manner, the false notches being very short, while the true notches are of sufficient size to admit of their receiving the straight edge of a movable plate, *f*, and to allow of the locking and unlocking of the shackle. Each slider is acted upon by a spring, *b*, that is applied to a bar, *c*, so as to press the slider up against the inside of the slotted face-plate *d* when released from the plate *f*. That edge of the plate or "knife" *f* which is nearest the notched edges of the sliders is straight and parallel to these edges, as shown in fig. 4. It is fitted to slide freely in grooves that are made through the boxed bearing *d*, and it receives a movement toward and from the sliders *e* in planes parallel thereto, so that when the shackle is unlocked, as in fig. 2, the straight edge of the plate or knife *f* will enter squarely the true notches in all the sliders, and when the shackle is locked the plate *f* recedes from these sliders and assumes the position shown in figs. 2 and 4. The plate or knife *f* is pivoted to two arms, *g* and *h*. The shortest arm, *g*, is pivoted to the frame C at *k*, and to the plate *f* at *i*, and the arm *h* is pivoted to plate *f* at *i*, and to the frame C at *l*. The outer end of this arm or lever *h* is slotted longitudinally, and through this slot a stud, *j*, projects, which is secured to the back-plate of the lock frame. The length of the slot through the outer end of arm *h* is such as to allow the plate C to have a free vibrating movement about its fixed pivot *p* for locking and unlocking the shackle. It is this slotted arm *h*, arranged as described, that causes the plate or knife *f* to

approach and recede from the sliders *e* in parallel planes, as to enter the true notches in these sliders when the shackle is unlocked. The spring *E* on stud *F* has a friction-catch formed on its end, which presses upon the tooth *m* that is formed on the plate *C*, and thus holds the plate *C* either in a locked or an unlocked position. The spring *D*, which is also applied to the stud *F*, is used for throwing out the nose of the shackle when this nose is released from the hooked bolt *a*, as shown in fig. 1.

In fig. 6 I have shown a mode of giving a parallel movement to the plate or knife *f*² by a single slotted lever, *h*², which is pivoted to the locking-plate *C* and to this knife *f*², and guided by a stationary stud, *j*². This knife, *f*², is connected to the frame *C* by means of two pins passing through oblique slots, so that when the frame *C* is moved said slots will guide the knife up to and from the true notches in the sliders.

In fig. 5, a slotted vibrating arm, *h*¹, and a vibrating arm, *g*¹, are pivoted to the plate or knife *f*¹ in such manner as to vibrate entirely through the true notches in the sliders *e*, both in locking and in unlocking the bolt, thereby allowing the sliders to rise to their places after each movement of the plate, and preventing an impression being taken of the positions of the sliders when the bolt is unlocked.

In both of these modifications of the device represented in figs. 1, 2, and 4, it will be seen that the straight edge of the knife is guided into and out of the true notches in the sliders with a parallel movement, and that the said knife is supported by, and caused to move with its bolt-plate about, the pivot thereof.

Having described my invention, what I claim as new, and desire to secure by Letters Patent, is—

1. In combination with an oscillating plate *C*, to which the notched sliders *e* are suitably applied, I claim the parallel moving plate or knife *f* attached to said plate and guide, substantially as described.
2. The combination of the plate or knife *f*, sliders *e*, and oscillating plate *C*, with a vibrating lever-arm which is guided and controlled by a fixed stud, *j*, or its equivalent, substantially as described.

WILSON BOHANNAN.
